No. 889,234.

PATENTED JUNE 2, 1908.

C. H. HOWARD, H. M. PFLAGER & C. T. WESTLAKE.
DRAFT GEAR FOR RAILROAD CARS.

APPLICATION FILED JULY 27, 1907.

UNITED STATES PATENT OFFICE.

CLARENCE H. HOWARD, HARRY M. PFLAGER, AND CHARLES T. WESTLAKE, OF ST. LOUIS, MISSOURI, ASSIGNORS TO TRANSOM DRAFT GEAR COMPANY, OF ST. LOUIS, MISSOURI, A CORPORATION OF DELAWARE.

DRAFT-GEAR FOR RAILROAD-CARS.

No. 889,234.

Specification of Letters Patent.

Patented June 2, 1908.

Application filed July 27, 1907. Serial No. 385,867.

To all whom it may concern:

Be it known that we, CLARENCE H. HOWARD, HARRY M. PFLAGER, and CHARLES T. WESTLAKE, citizens of the United States, residing at St. Louis, in the State of Missouri, have invented a new and useful Improvement in Draft-Gear for Railroad-Cars, of which the following is a specification.

Our invention relates to that class of draft-gear in which the "buffing" and "draft" springs are respectively applied, without the use of follower-plates, directly to the front and rear sides of the body-bolster of a railroad car underframe, and is in the nature of a modification of that for which Letters Patent were granted to Harry M. Pflager, January 23, 1906, number 810,805, for improvement in draft-gear for railroad cars.

Our invention is particularly applicable to a metallic car underframe in which the distance between the two middle longitudinal sills, which butt against the rear side of the body-bolsters, is insufficient for assembling and operating the draft-springs between the said sills in alignment with the buffing-springs against the front side of the bolster as in the said patent, and our invention has for its object, to obviate this difficulty, to increase the efficiency and strength of the buffing-springs, and to insure a more positive self-centering or return of the draft-gear to its normal position on removal of the stress therefrom.

It consists in features of novelty as hereinafter described and claimed, reference being had to the accompanying drawing forming part of this specification, whereon,

Figure 1, is a horizontal section, partly in top plan view, of our improved draft-gear applied to one of the body-bolsters and two middle longitudinal sills of a metallic car underframe, on line 1, 1, in Fig. 2; Fig. 2, a front view of the bolster seen in Fig. 1, omitting the draft-gear, and Fig. 3, a vertical transverse section through the bolster, and longitudinal section through the draft-gear on line 3, 3, in Fig. 1.

Like letters and numerals of reference denote like parts in all the figures.

50 *a* represents one of the body-bolsters, and *b* the two middle longitudinal sills of a metallic car underframe, having our improved draft-gear applied thereto, the bolster *a* in the present case being of the cast steel type,

preferably I-shaped in cross section integral throughout, and having the body-center-plate 1 perforated centrally for the king-bolt in the usual manner.

The middle longitudinal sills *b* in the present case are shown as channel irons arranged opposite to each other at a short distance apart, one on each side of, and equidistant from the longitudinal center of the underframe, with their flanges outward, the ends of the sills *b* butting against the rear side (or web) 2 of the bolster *a* having rearwardly projecting brackets 3, to which the end portions of the sills *b* are laterally secured by rivets 4, or otherwise, as found most suitable, the sills *b* being reinforced at the top and connected together at their end portions by an angle-bar 5 as shown. Or the sills *b* may be of any other suitable shape and material according to the type of underframe used.

Along the front side (or web) 2 of the bolster *a* in the same horizontal plane with each other, are formed three cylindrical pockets, to wit; a middle pocket 6 alined to the longitudinal center of the underframe, and a pocket 6' on each side of the middle pocket 6, and preferably alined to the corresponding middle sill *b*, or thereabout, the pockets 6, 6', being adapted to receive the inner ends of the "buffing" springs 7, 7'. *c* is the draw-bar, in the inner end of which are formed three cylindrical pockets 8, 8', corresponding to the pockets 6, 6', and adapted to receive the outer ends of the "buffing" springs 7, 7'.

Along the rear side (or web) 2 of the bolster *a* in the plane of, but spaced further apart than the pockets 6, 6', are formed two cylindrical pockets 9, one on each side of and equidistant from the longitudinal center of the underframe, and at a suitable distance from the outermost side of the corresponding middle sill *b* toward the end of the bolster *a*, the pockets 9 being adapted to receive the inner ends of the "draft" springs 10, while the outer end of each spring 10 is engaged by a yoke *d* having its arms 11 coupled at their free ends by a pin 12 to the draw-bar *c* (preferably at its inner end adjacent to the corresponding pocket 8') and adapted to play through openings 13 (seen in Fig. 2) formed therefor through the web 2 of the bolster *a*.

By the above construction of draft-gear the "buffing" stress of the springs 7' is trans-

mitted directly to the ends of and longitudinally through the middle sills *b*, or along the line of maximum resistance of the under-frame, the strength and efficiency of the 5 springs *7'* being increased by the additional middle spring *7*. Furthermore, by spacing the "draft" springs *10* further apart than the "buffing" springs *7, 7'*, and adapting them to bear against the bolster *a* at points outside 10 the sills *b* between them and the side sills (not shown) the resiliency of the "draft" spring in compression when pulling on a curve is increased, and the draw-bar *c* returned more positively thereby to its normal position on 15 the car leaving the curve.

What we claim as our invention and desire to secure by Letters Patent is

In draft-gear of the character described, the combination with the middle longitudinal sills and body-bolster of a car under-frame, of a draw-bar, a "buffing" spring 20 adapted to bear at one end against the front

side of the bolster in alinement, or thereabout, with each of the said sills, and at its other end against the draw-bar, a "draft" 25 spring adapted to bear at one end against the rear side of the bolster adjacent to the outermost side of each of the said sills, and a yoke adapted to engage the other end of the "draft" spring, the arms of the said yoke 30 being coupled at their free ends to the draw-bar and adapted to play through the bolster, substantially as described and for the purpose set forth.

In testimony whereof we have signed our 35 names to this specification in the presence of two subscribing witnesses.

CLARENCE H. HOWARD.
HARRY M. PFLAGER.
CHARLES T. WESTLAKE.
